GREASE DISPENSING CONTAINER

Filed Nov. 17, 1927

Inventor
Bayard W. Mendenhall

By Zabel & Banning Attn:

UNITED STATES PATENT OFFICE

BAYARD W. MENDENHALL, OF SALT LAKE CITY, UTAH

GREASE-DISPENSING CONTAINER

Application filed November 17, 1927. Serial No. 233,852.

This invention relates to grease dispensing containers and has for its object the provision of a container which may be used for shipping grease or similar material and which can readily be changed into a self-dispensing container by the retail user. In so far as I am aware, in spite of the demand for a device of this character the present means of marketing grease such as the hard oil used for 10 automobile and other bearings is to ship the same in an ordinary container and then in utilizing it to remove the head of the container and scoop the lubricant out from time to time as it is required. This has the difficulty 15 of leaving the barrel or container open to the dust and other impurities and occasions considerable loss of time and a waste of the lubricant.

It is the purpose of this invention to provide means therefore which will eliminate the aforementioned difficulties and enable the retail user or dispenser to utilize the shipping container directly as a dispensing means.

25 A more specific purpose of this invention is to provide in connection with the shipping container a dispensing head which carries means for readily attaching it to the shipping container upon removal of the shipping head 30 and which carries in addition a guide member and a plunger for forcing the contents of the container outwardly at the bottom thereof when air pressure is applied above the plunger through the dispensing head.

35 Other and more specific objects and advantages of the invention will appear as the description proceeds when taken in connection with the accompanying drawings; however, I wish it to be distinctly understood that 40 I do not intend to limit myself to the exact details shown and described, but that I am to avail myself of all such modifications as would occur to one skilled in this art and as fall within the scope of the claims.

45 In the drawings:

Fig. 1 is a sectional view taken through the shipping container;

50 Fig. 2 is a similar sectional view with the shipping head removed and the dispensing head in place thereon and further showing

the dispensing conduit leading from the container;

Fig. 3 is a fragmentary section showing the plunger in a lowermost position within the container; and

Fig. 4 is a detailed view of a split ring used in attaching the shipping and dispensing heads to the container.

Referring now in detail to the drawings, the numeral 5 indicates a cylindrical container usually constructed of sheet metal, which container is provided in the bottom portion thereof with an outwardly bent portion 6 and the inset bottom portion 7. The bottom forms with the portion 6 a pocket 8 for a purpose which will presently appear.

Centrally disposed in the bottom 7 is the recess 9 and at one side of the recess 9 is provided an outlet opening 10 normally closed by a plug 11. The top of the container 5 as shown in Fig. 1 has an outwardly extending flange 12 upon which the outwardly extending flange 13 of the shipping head or cover 14 is adapted to rest. This cover 14 as shown is depressed inwardly of the flange 13 so as to fit snugly within the top of the container. The two flanges 12 and 13 are held rigidly in engagement by means of a solid ring 15 and the split ring 16 consisting of the halves 17 and 18 as shown clearly in Fig. 4. These flanges and rings are provided with closely spaced bolt holes adapted to receive the clamping bolts 19. Thus, when the head 14 is applied as shown in Fig. 1 and the plug 11 is in place, the container 5 forms a tight shipping container in which lubricant may be transported from place to place. The outwardly extending flanges 6 and 12 form rolling edges on which the container may be run in loading or unloading it so as to avoid bending or denting the body thereof.

Now, when the container is received by the retailers of the lubricant, the shipping head or closure 14 is removed and a dispensing head 20 is substituted for it. This dispensing head is secured in substantially the same manner as the head 14 and carries a guide rod 21 extending centrally therefrom downwardly into the container and adapted to fit in the recess 9 at its lower end so as to

be held against lateral movement. This guide rod 21 in turn has slidably mounted thereon the piston or plunger 22 which has an elongated hub or bearing 23 engaging the rod 21 to prevent wabbling or tipping of the plunger within the container. A flexible cup leather 24 is mounted in the rim of the plunger and projects downwardly therefrom toward the bottom of the container. The plug 11 is removed and replaced by the pipe section 25 communicating with the strainer casing 26, an outlet controlled valve 27, through a metering device 28 to the discharge pipe 29. This may lead to any place where it is desired to use the lubricant.

It will be noted that the dispensing head 20 is concave on its lower surface so as to permit the plunger 22 and its elongated hub 23 to move up closely against the head 20 in fitting the dispensing head to a full container. The dispensing head is also provided with an inlet 30 to which an air hose 31 may be connected so as to supply air pressure within the container to force the plunger downwardly and force the lubricant in the container out through the discharge opening. As the plunger approaches the bottom of the container, the cup leather 24 as it extends down below the lower face of the plunger would, unless some provision were made for it, be doubled up beneath the plunger and bent out of proper shape. In order to avoid this, the recess 8 is provided which permits the cup leather to expand outwardly as the plunger approaches the bottom of the container as shown in Fig. 3 and this avoids any doubling or breaking of the cup leather.

From the above description, it is thought that the construction and the use of my improved dispensing container will be clear to those skilled in this art. However, a few of the uses to which this device may be put is in the lubrication of machinery such as mine car wheels which require only a low pressure somewhat less than 200 pounds per square inch to force the lubricant in the bearing to be lubricated, also lubricating automobiles and similar machinery by using a flexible hose on the end of the discharge pipe with the lever type booster pump and the coupling on the end of the flexible hose similar to the well known alemite type; also in lubricating industrial machinery by running pipes directly from the discharge pipe of the container to the points where it is desired to apply the lubricant.

In all of these uses my device has the advantage that the container may be permanently located in any convenient place and the discharge pipe can be run to a convenient point for use without requiring the necessity of an additional container into which the lubricant must be emptied from the shipping container.

Having thus described my invention,

what I claim and desire to secure by Letters Patent of the United States is:

1. A grease storing and dispensing device comprising a cylindrical container having an outlet opening formed in the bottom thereof, a removable head for said container having a piston guide rod rigidly secured thereto and extending to the bottom of said container, receiving means in the bottom of said container into engagement with which the lower end of said guide rod is slideable to hold the same against lateral movement, a plunger freely slideable on said guide rod and means on said head for admitting air under pressure into said container above said plunger, said plunger having a flexible sleeve secured to the rim thereof and said container having an annular recess at the lower end thereof to receive said sleeve. 70 75 80

2. A grease storing and dispensing container comprising a substantially cylindrical shell, a closure permanently closing one end of said shell and forming with the end of said shell an outwardly extending rim adapted to serve as a rolling edge for said shell and forming within said rim an annular recess of greater diameter than said shell, said closure having an outlet aperture therein, a removable head for the other end of said container having a guide rod secured thereto and extending to said closure, a plunger freely slideable on said rod, and an annular flexible member on said plunger adapted to extend into said recess when said plunger is in its lowermost position. 90 95 100

3. A combined shipping container and grease dispensing head comprising a substantially cylindrical shell having a permanent closure at one end formed with an outlet aperture and having seating means therein adapted to receive and hold a guide rod from lateral movement, a closure for the other end of said container readily attachable thereto, said closure having rigidly mounted thereon a guide rod which extends the length of said container and engages said seating means, a piston slideable on said rod, and means on said second named closure to admit air above said piston, said permanent closure and seating means permitting said piston to move substantially into engagement with the inner surface of said permanent closure whereby to expel practically all of the contents of said container. 110 115 120

In witness whereof I hereunto subscribe my name this fourth day of November A. D. 1927.

BAYARD W. MENDENHALL.
